CLAIM

The ornamental design for a breathing tube connector for a respiratory gas exchange monitor, as shown and described.

DESCRIPTION

FIG. 1 is a perspective view of a breathing tube connector for a respiratory gas exchange monitor connected to a breathing tube;

FIG. 2 is a top view thereof;

FIG. 3 is a left side view thereof;

FIG. 4 is a rear view thereof;

FIG. 5 is a right side view thereof;

FIG. 6 is a front view thereof;

FIG. 7 is a bottom view thereof;

FIG. 8 is a perspective view of the breathing tube connector for a respiratory gas exchange monitor of FIG. 1;

FIG. 9 is a top view thereof;

FIG. 10 is a left side view thereof;

FIG. 11 is a rear view thereof;

FIG. 12 is a right side view thereof;

FIG. 13 is a front view thereof; and,

FIG. 14 is a bottom view thereof.

The broken lines showing of the breathing tube is for the purpose of illustrating environmental structure and forms no part of the claimed design. All other broken lines depict portions of the breathing tube connector for a respiratory gas exchange monitor that forms no part of the claimed design.
